(57) **CLAIM**

The ornamental design for a recycling container, as shown and described.

DESCRIPTION

FIG. 1 is a left, front perspective view showing a recycling container according to the invention;

FIG. 2 is a front view thereof;

FIG. 3 is a side view thereof;

FIG. 4 is a top view thereof; and,

FIG. 5 is a bottom view thereof.

The small element shown in broken lines in FIGS. 2 and 4 is included for the purpose of illustrating environment and forms no part of the claimed design.
